UNITED STATES PATENT OFFICE.

JOHN R. DIMICK, OF SALEM, OREGON.

MACHINE FOR TOPPING AND CLEANING ONION-SETS.

936,224.

Specification of Letters Patent.

Patented Oct. 5, 1909.

Application filed March 16, 1909. Serial No. 483,778.

To all whom it may concern:

Be it known that I, JOHN R. DIMICK, a citizen of the United States, residing at Salem, in the county of Marion and State 5 of Oregon, have invented certain new and useful Improvements in Machines for Topping and Cleaning Onion-Sets; and I do hereby declare the following to be a full, clear, and exact description of the invention, such as will enable others skilled in the 10 art to which it appertains to make and use the same.

My invention relates to new and useful improvements in machines for topping and 15 cleaning onion sets and my object is to provide a device of this class which will separate the bunches of sets and remove the dead stalks therefrom.

A further object is to provide means for 20 passing the sets over a grating, whereby the stalks and chaff occasioned by separating the sets will pass into a separate compartment from the sets, and a still further object is to provide means for collecting the chaff, 25 etc. and remove the same from the machine.

Other objects and advantages will be hereinafter referred to and more particularly pointed out in the claims.

Referring to the drawings forming part 30 of this application, Figure 1 is a side elevation of the topping and cleaning device, complete. Fig. 2 is a similar view from the opposite side of the machine, and, Fig. 3 is a longitudinal central sectional view through 35 the machine. Fig. 4 is a plan view of the invention.

Referring to the drawings in which similar reference numerals designate corresponding parts throughout the several views, 1 40 and 2 indicate standards, which standards are mounted on a suitable base 3 and are arranged in pairs, the upper ends of the standards being connected together by suitable frame pieces 4.

Slidably mounted between the standards 1 and 2 is a frame 5, the lower edges of the side walls of said frame having track ways 6 thereon, which track ways are adapted to engage bearing rollers 7 rotatably mounted 50 on the standards, said frame being adapted to move longitudinally over said rollers.

Extending from wall to wall of the frame 5 and from end to end thereof is a floor 8, a portion of which is provided with slots 9 55 to form ribs 10, over which the onion sets are adapted to pass, the slots 9 affording a

passage for the chaff, etc., occasioned by separating the onion sets, while the sets themselves pass to the lower end of the floor 8, where they are discharged into any suitable receptacle. 60

The frame 5 and floor 8 are placed at an incline so that the sets will readily pass from the upper to the lower end of the frame, the upper end of the frame having 65 flanges 11 surrounding the same to form a hopper 12, into which the sets in their original state are deposited and immediately above the hopper are positioned a plurality of beaters 13, the lower ends of which are 70 covered with shields 14, preferably of rubber, or like pliable material, so that when the beaters are moved into engagement with the sets, said sets will not be mashed or otherwise mutilated by the beaters. 75

The beaters 13 are mounted in cross bars 15, which cross bars are carried by the arms 16, the inner ends of said arms being hingedly secured to a bar 17 carried by a rack 18 and said arms and parts carried thereby are 80 raised and lowered by attaching the cranked portion 19 of a crank shaft 20 to bearings 21, on said arms, the shaft 20 being in turn rotatably mounted in bearings 22 on the standards 1, the rotation of said shaft forcing the 85 beaters 13 into engagement with the sets in the hopper.

The rack 18 is slidably mounted on bearing rollers 23 and 24, which are carried by the posts 1 and 2 and is moved longitudinally 90 by the action of the arms 16, said rack being provided with a plurality of cross bars 25, each of which is provided with a plurality of depending teeth 26, on the lower ends of which are arranged shields 27, 95 the teeth being adapted to move the separated sets along the floor 8 and over the ribs 10, the forward end set of teeth being attached to a pivoted bar 28 of said rack, so that when the rack is moved toward the 100 hopper 12, the bar 28 will tilt and permit the teeth to pass over the sets, but will immediately swing to a vertical position when the rack is moved in the opposite direction, the swinging movement of the bar being limited in one direction by means of tongues 29, which tongues are fixed to the pivoted bar 28 105 and extend over and engage parts of the rack 18. The teeth attached to the cross bar 25 are fixed in a vertical position and are adapted to agitate the sets as they move toward the lower end of the floor 8, thereby

110

separating the sets from the chaff, etc., and forcing the chaff through the slots between the ribs 10, while the sets are moved to the lower end of the floor, and as the beaters 5 are given a raking movement as well as a pounding motion, the beaters in their lowered position moving toward the rack 18, the sets will be constantly fed into engagement with the rack.

16 The frame 5 is moved longitudinally by means of a pitman 30, one end of which is pivotally secured to a crank arm 31 on the shaft 20, while the opposite end thereof is pivotally secured to a crank arm 32 on a 15 shaft 33, said shaft having cranked portions 34, to which are pivotally secured pitmen 35, the opposite ends of said pitmen being hingedly secured to a chaff board 36 arranged between the walls of the frame 5, the 20 pitmen 30 and 35 and the crank arms 31 and 32 being so arranged that the shaft 33 will be rocked back and forth while the shaft 20 makes a complete revolution. The chaff board 36 is so inclined as to direct the particles 25 falling thereon into a receptacle 37, the bottom 38 of the receptacle being likewise inclined toward one end of the receptacle, at which end is positioned a suction fan 39, which is adapted to collect the chaff, etc., 30 from the receptacle and discharge the same at a point a distance from the machine through any suitable form of conduit pipe 40.

A shaft 41 is rotatably mounted below the frame 5 and has at one end thereof a belt 35 wheel 42, while at the opposite end of the shaft 41 is secured a balance wheel 43, which balance wheel also serves as a belt wheel for a belt 44, said belt also passing around a pulley 45, attached to the shaft carrying the 40 fan 39 and by which means the fan is driven, while the shaft 20 and parts connected thereto are driven by attaching to the shaft 41 a sprocket 46, around which and a similar sprocket 47 on the shaft 20, extends a 45 sprocket chain 48.

In operation, the onion sets, in their original condition, are deposited in the hopper 12, when the machinery is started by applying power to the belt wheel 42, this operation 50 directing the beaters into engagement with the sets placed in the hopper, which will result in separating the bunches into single sets and at the same time reducing the stalk upon which the sets grow, into small particles, so that as the sets are gradually moved 55 toward the lower end of the floor 8, the husks or chaff and particles of the stalk will descend between the ribs and be carried away by the fan 39, while the sets will be carried 60 beyond the receptacle 37 and deposited directly upon the floor or into any suitable receptacle.

It will thus be seen that I have provided 65 an efficient and durable means for separating and cleaning the onion sets and one wherein

the sets will not be mutilated or otherwise destroyed while being so treated and it will likewise be seen that I have provided convenient means for removing the chaff, etc. 70 from the sets and conveying the same to any suitable discharge point.

What I claim is:

1. A machine of the class described, comprising the combination with standards; of a frame movably mounted between said 75 standards, a floor in said frame having slots therein to form ribs, means to move said frame longitudinally, a rack slidably mounted above the frame, a plurality of teeth carried by said rack adapted to agitate and 80 move the contents of the frame, beaters above said floor and pivoted arms carrying said beaters, means to swing said arms upwardly and downwardly and to move the beaters into contact with the hopper contents, the action of said arms moving the rack longitudinally. 85

2. A machine of the class described, comprising the combination with a movable frame having a floor therein, a hopper at 90 one end of said frame, a rack slidably mounted above the frame, teeth carried by the rack adapted to extend into said frame and in juxtaposition to said floor, a plurality of beaters above said floor, pivoted arms carrying said beaters, means to swing said arms upwardly and downwardly and move the beaters into engagement with the contents of the hopper, the movement of said arms moving the rack longitudinally, means to 100 move the frame longitudinally, ribs in said floor between which particles of the contents of the floor may be passed and means to gather and convey said particles to a distance from the machine. 105

3. A machine of the class described, comprising the combination with a slidably mounted frame having a floor therein, said floor being provided with ribs and a hopper at one end of said frame; of a plurality of beaters adapted to engage and disintegrate the contents of the hopper, arms carrying said beaters, a rack having fingers adapted to engage and agitate the particles on said floor, said arms being secured to the rack 110 and means to operate said beaters and move the frame and rack longitudinally. 115

4. A machine of the class described, comprising the combination with a frame having a floor therein; of a slidably mounted 120 rack, teeth depending from said rack, flexible shields on said teeth, a plurality of beaters, arms carrying said beaters, means to hingedly secure the arms to the rack, shields on said beaters and means to swing said arms upwardly and downwardly and to move the beaters into contact with the hopper contents, the action of said arms moving said rack longitudinally, and means to move said frame longitudinally. 125

5. A machine of the class described, comprising a frame having a floor therein, a slidably mounted rack, teeth depending from said rack, a plurality of arms, beaters carried by said arms, a hopper, means for pivotally connecting said arms to said rack, and means to swing said arms upwardly and downwardly and to move the beaters into contact with the hopper contents, the action 5 of said arms moving said rack longitudinally, and means to move said frame longitudinally, a pivoted bar arranged at the forward end of said frame, said bar being provided with a set of depending teeth, and having an overhanging stop at its rear edge. 15

In testimony whereof I have signed my name to this specification in the presence of two subscribing witnesses.

JOHN R. DIMICK.
